UNITED STATES PATENT OFFICE.

ALEXANDER MACDOUGALL, OF BAKER, OREGON.

DISPLAY CONTAINER.

Application filed August 19, 1926. Serial No. 130,220.

This invention relates to display containers and has for its main object the provision of means whereby the articles to be sold from the container may present a pleasing appearance at all times. This object is attained by the provision of a container having a movable supporting member adapted to be positioned on the bottom of the container when the latter is full, and capable 10 of vertical adjustment above said bottom with a view of varying the capacity of the container from time to time as part of its contents is removed, with a view of giving the container the appearance of being full. 15 For a complete understanding of the invention, reference is to be had to the accompanying drawings forming a part of this specification.

In the drawings:
20 Figure 1 is a side view of a container such as a candy pail.
Figure 2 is a sectional view showing the supporting member positioned near the top of the container.
25 Figure 3 is a section on the line 3—3 of Figure 2.
Figure 4 is a vertical section showing the supporting member at the bottom of the container when the latter is full.
30 Figure 5 is a detail vertical section of the container and the supporting shelves.
Figure 6 is a similar view in plan.
Figure 7 is a similar view in front elevation.
35 Figure 8 is a view similar to Figure 6, with a guard in position.
Figure 9 is a perspective view of one of the guards.

Figure 10 is a detail view of a modified 40 construction detail.
Figure 11 is a sectional view illustrating the application of the invention to a rectangular container.

Referring to the drawings in detail, the 45 reference character C designates a container which may be a candy pail or any other receptacle. The pail may be provided with the usual bail b. Disposed within the container in peripherally-spaced relation are a 50 number of standards S extending substantially the depth of the container. The standard comprises a metal sheath 10 having inturned edges 11 as shown more clearly by Figure 6. Disposed within this metal 55 sheath 10 is a channeled member 12 having outturned edges 13 in juxtaposition to the

inturned edges 11 of the sheath 10. The channeled member 12 is perforated at longitudinally-spaced intervals with the side walls 14, the perforations in the side walls 60 being in alignment. The front of the channel 12 is provided with a number of cut-out portions 15 leaving between successive cut-out portions a portion of metal adjacent to the perforation and forming a ledge 16. A 65 projecting member 18 has outturned ends 19 which are adapted to pass through the perforations in the channels 12 forming a pivotal connection therewith. It will be seen that the pivoted extensions 18 may move 70 upwardly into planes substantially contiguous with the inner walls of the receptacle and are supported in transverse planes by the ledges 16, as shown more clearly by Figure 5. 75

In a container such as that represented by Figure 1 wherein the sides slope or converge toward each other, it is desirable that the projections be shorter progressively in accordance with the slope of said walls. 80 For this purpose the projections or shelves 18 are progressively shorter from top to bottom of the container, as shown by Figure 2.

A supporting member 20 is provided and 85 is adapted to be positioned within the receptacle C and will conform to the inner contour of the latter. The supporting member 20 is adapted to be successively carried by the shelves 18 and also moved 90 from the bottom of the container and successively to the top thereof as the articles sold are removed.

Figure 2 shows a container in which the 95 supporting member 20 is in position on the shelves 18 after the major portion of the contents of the container has been removed. The supporting member 20 is provided with cut-out portions 21 at the periphery thereof, as shown in Fig. 3, for a purpose which will 100 be presently described. The supporting member 20 is provided with lifting ribbons 22 for raising the supporting member as the contents of the container are diminished.

Referring to Figure 4, the matter of filling 105 the container will now be described. The supporting member 20 rests on the bottom. Guards 23, each consisting of a U-shaped metal piece as shown in perspective in Figure 9, are positioned over the channels 12 110 with the shelves 18 in planes substantially contiguous to the inner walls of the recep-

tacle. The cut-out portions 21 in the supporting member 20 facilitate the positioning of the latter into the container before the filling thereof and are sometimes necessary 5 to permit the supporting member to be positioned, with the guards 23 extending into said cut-out portions. As the receptacle is filled either by successive layers or progressively in bulk, the guards 23 are raised so that 10 the contents of the receptacle will maintain the shelves 18 in their non-supporting position as shown. It will be understood that after the container is filled, the guards will be removed completely. Then as the 15 contents of the container are gradually removed, the bottom 20 will be raised so that the latter will be supported by the first or lowest tier of shelves 18 and then to the next higher tier of shelves and so on, until the top tier is 20 reached.

The preferred embodiment of my invention has been described but it will be understood that the invention is not limited to the exact construction. For example in lieu of 25 the metal piece 10 as shown by Figure 6, the inner wall of the receptacle C may be grooved as at 24 to receive the outturned end 13 of the channel 12. It will also be understood that the contour of the container may 30 be rectangular instead of round as illustrated in Figure 11, as described by the reference character C'. The supporting member will of course be rectangular in conformance to the interior contour of the rectangular container, but in other respects the construction 35 and arrangement of the parts may be the same. It will be understood that other changes in the construction and arrangement of parts may be made without departing 40 from the invention as defined by the appended claims.

Having thus described my invention, what I claim is:

1. A display container comprising a receptacle, a plurality of standards secured to the walls of said receptacle in peripherally-spaced relation, a plurality of longitudinally-spaced shelves pivotally connected to said standards, a support carried by said shelves, and means secured to said support for lifting the latter from the bottom of the container toward the top thereof from one set of shelves to another.
2. A display container comprising a receptacle, a plurality of shelves in each of a plurality of longitudinally-spaced planes above the bottom of said receptacle, the shelves in each of said planes being in peripherally-spaced relation, means pivotally connecting said shelves to the inner walls of said receptacle, a supporting member adapt-

ed to be placed on said shelves in successive planes above the bottom of said receptacle, and means secured to said supporting member for raising the latter from the bottom of the container toward the top in successive planes above the bottom of said receptacle. 65

3. A display container comprising a receptacle, a plurality of peripherally-spaced shelves above the bottom of said receptacle, 70 means pivotally connecting said shelves to the inner walls of said receptacle, a supporting member adapted to be carried by said shelves above the bottom of said receptacle, and means secured to said supporting member for raising it from below said shelves to position thereon.

4. A display container comprising a receptacle having a plurality of longitudinally-extending and peripherally-spaced grooves, 75 a plurality of peripherally-spaced shelves above the bottom of said receptacle, means pivotally connecting said shelves in said grooves, and a supporting member adapted to be carried by said shelves above the bottom of said receptacle. 80

5. A display container comprising a receptacle having walls converging toward each other, a plurality of shelves in each of a plurality of planes, said shelves being progressively shorter in planes corresponding to said converging walls, means connecting said shelves to the inner walls of said receptacle, and a supporting member adapted to be carried successively by said shelves in each of 90 said planes.

6. A display container comprising a receptacle, a plurality of channeled standards secured to the inner walls of said receptacle in peripherally-spaced relation, a plurality of shelves pivotally secured to said channeled standards above the bottom of said receptacle, and a supporting member adapted to be carried by said shelves above the bottom of said receptacle. 100

7. A display container comprising a receptacle, a plurality of shelves movably secured to the inner walls of said receptacle in peripheral and longitudinal spaced relation, said shelves being adapted to be moved from planes transverse to said walls to planes contiguous with the walls of said receptacles, removable cover members for said shelves when the latter are in planes contiguous with said receptacle walls, and a supporting member adapted to be carried by said shelves when the latter are in planes transverse to said receptacle walls and said covers are removed. 110

In testimony whereof, I hereunto affix my 115 signature.

ALEXANDER MACDOUGALL.
